UNITED STATES PATENT OFFICE.

EMIL JAGENBERG, OF DUSSELDORF, GERMANY.

PAPER-FEEDING MACHINE.

1,159,498.

Specification of Letters Patent.

Patented Nov. 9, 1915.

Application filed August 4, 1914. Serial No. 854,910.

To all whom it may concern:

Be it known that I, EMIL JAGENBERG, a subject of the German Emperor, and residing at 107 Himmelgeisterstrasse, Dusseldorf, Germany, manufacturer, have invented 5 certain new and useful Improvements in Paper-Feeding Machines, of which the following is a specification.

The present invention relates to an arrangement for drawing labels from a pile 10 and conveying them farther.

The essential feature of the new arrangement consists above all in the adjustability of the rollers or the endless conveyer belts 15 respectively, which convey the labels drawn from the pile. This adjustability allows of the arrangement being used for labels of any width.

A further feature of the present invention 20 consists in a device for accurately regulating the drawing-off of the labels.

In the accompanying drawings Figure 1 is a side elevation, Fig. 2 is a longitudinal part section, Fig. 3 is a plan, and Figs. 4 25 and 5 are views of the automatic pawl-engaging gear in two different positions. Fig. 6 is a side elevation and Fig. 7 is a plan of a modified constructional form.

On the body 1 of the machine is secured 30 the frame 2 by means of screws 3. In this frame are revolvably journaled two shafts 4, 5, on which rollers 6 and toothed wheels 7 are fitted. Over the rollers 6 run endless rubber bands 8 and over the toothed wheels 35 7 an endless chain 9. On the said rubber bands lies a pile of labels 10 which is supported by the side walls 11, which by means of ears 12 and screws 13 are adjustably fitted to the frame 2. Between the shafts 4, 40 5 a shaft 14 is journaled in the frame 2, on which shaft 14 are loosely fitted two arms 15, the free ends of which are coupled by a rod 16 arranged alongside of shaft 5, and on which several thin bars 18 are secured by 45 means of clips 17, the free ends of said bars 18 bearing against the shaft 14. On the rod 16 are further fitted two rods 19, which extend through clips 20 on arms 21. By adjusting these rods 19, after the clips 20 50 have been loosened, the incline of the bars 18 can be varied. On these bars the rear end of the pile of labels rests, so that the rubber bands support the front end only. The front edges of the labels bear against 55 rails 23 which are slidably fitted in brackets 22. These brackets 22 are displaceably fitted

on a bar 24 secured in the frame 2. The rails 23 are so set, that between their lower ends and the rubber bands a space is left free, which corresponds to the thickness of 60 the individual sheets in the pile.

Outside of the frame 2 a sprocket wheel 25 is loosely fitted on shaft 4, and attached to it is a flat clutch disk 26. On the same shaft 4 is further fitted a ratchet wheel 27, 65 which is attached to the corresponding clutch disk 28, adapted to engage with the clutch disk 26. This ratchet wheel 27 can be axially displaced on the shaft 4, but cannot rotate thereon, being prevented from 70 doing so by a tongue and groove 29. Against the hub of the ratchet wheel bears a spring 30 which is fitted to the end of shaft 4 and is there held by means of the nut 31. The spring therefore presses the two clutch 75 members tightly against each other. For increasing the friction a leather disk 32 may be placed between the said members. In the teeth of the ratchet wheel 27 engages a pawl 33, which is pivotally fitted to the 80 frame 2 and has two arms 34, 35, of which the one 34 lies in front of a toothed wheel 36 which is revolvably fitted to the frame 2. On this wheel a pin 38 with a roller 39 is adjustably fitted in a slot 37. When the 85 wheel revolves, this roller bears against the arm 34 and thereby disengages the pawl 33. To the other arm 35 is linked a rod 40 and fitted a spring 41, which tends to press the 90 pawl 33 into the ratchet teeth. Ratchet 95 wheel 27 is furthermore engaged by a second pawl *c* carried by a hand lever *b* that turns on a shaft *a*. This pawl is adapted to lock the wheel during the back stroke of pawl 33, the weight of lever *b* forcing pawl *c* 95 against the wheel, while the lever permits the pawl to be lifted out of engagement with the wheel, when the latter is to be turned back. The free end of the rod 40 is secured in the lower end of a lever 42, which is pivotally fitted to a bracket 43. This bracket 100 is adjustably fitted by means of screws 44 to the body 1 of the machine, the same as the bracket 43. In these two brackets a shaft 45 is revolvably journaled and a rod 46 105 rigidly fixed. On the latter rod 46 thin bars or members 47 are secured, which extend between the rubber bands 8 and rest slidably upon the shaft 4. On the shaft 45 is fitted a sleeve 48, from which a part 49 110 is cut away. To the same shaft is also clamped a curved bar 50, the free end of

2
 which bears against an inclined plate 51, which is secured to the rod 46. On the shaft 52 journaled in bracket 43 and carrying the lever 42 is fitted a second lever 53, the end 5 of which engages under the cut-out 49, and can pass through the end of the lever, when the shaft 45 is so turned, that the edge 54 of the cut-out is lifted (Fig. 5). A spring 67, which acts on an arm 68 on shaft 45, 10 tends to hold this edge 54 down.

In the brackets 43, 43^a are further journaled two shafts 55, 55, of which the lower one carries a toothed wheel 56 on its outside end. These shafts are either smooth, 15 as shown in Fig. 3, or are provided with rollers 57, 58, around which endless wire coils 59 and rubber bands 60 are laid, which are also laid around the correspondingly shaped rollers 61, 62 on the shafts 64 which 20 are journaled in the brackets 63, 63^a. The brackets 63, 63^a are rigidly connected with the brackets 43, 43^a and likewise adjustably fitted to the machine body 1. Over the sprockets 56, 25, 36 and over a sprocket 65 25 journaled in the machine body 1 an endless chain 66 is laid, which runs over a further sprocket, not shown in the drawing.

When the pawl 33 is engaged (Figs. 1, 2, 4) the shaft 4 is held, the rubber bands 8 30 are arrested and the clutch disks 26, 28 slide on each other. When the roller 39 disengages the pawl 33, the friction between the two clutch members will cause the shaft 4 to revolve and thereby the rubber bands 8 35 will begin to travel. These rubber bands then draw the lowermost sheet from the pile, which thereupon glides along the bars 47 toward the rollers 55. The pawl 33 can be disengaged, as the lever 53 presses against the cut-out 49 from the right and thereby 40 turns the shaft 45 until it engages in front of the edge 54, whereupon the spring 67 immediately turns the shaft 45 backward, so that the lever 53 bears against the edge 54 45 when the roller 39 has left the arm 34 and the spring 41 again tends to engage the pawl. The pawl 33 thus remains disengaged (Fig. 4) while the sheet which has been drawn 50 from the pile is pushed between the rollers 55 or between the bands 60 and the coils 59 55 respectively. As soon as the front edge of the sheet arrives there, it lifts the arm 50 (Fig. 5), so that shaft 45 is turned. There-

by the edge 54 is lifted and drawn off the end of the lever 53, which can now pass 55 through the cut-out 49 and reengage the pawl 33. The shaft 4 is then again arrested, so that the rubber bands cease to travel. The sheet is advanced by the rollers 55 or the bands 60 and coils 59 respectively 60 and as soon as it has passed the arm 50, the latter again drops down and turns the sleeve back into the position shown in Fig. 2. The roller 39 then again strikes against the arm 34, disengages the pawl and the next sheet is drawn off. The distance between the shaft 4 and the shafts 55 is adjusted by displacing the brackets 43, 43^a and 65 63, 63^a in such a manner, that it corresponds exactly with the width of the sheets in the 70 pile. The rubber bands 8 are therefore arrested as soon as the more rapidly traveling rollers 55 seize the sheet drawn off the pile. It is therefore impossible for the sheet to be torn. 75

I claim:

1. A paper feeding device comprising a pair of shafts, a plurality of feed bands engaging the shafts, a rod arranged alongside of one of the shafts, means for vertically adjusting said rod, a support intermediate the shafts, and a plurality of bars mounted on the rod and engaging the support.

2. Arrangement for drawing-off labels from a pile, consisting of a belt-conveyer 85 for seizing the lowermost sheet of a pile of sheets, a shaft for the said conveyer, a first clutch member, and a ratchet wheel rigidly fitted to said shaft, a second driven clutch member fitted loose on said shaft, a spring 90 tending to press the two said clutch members against each other, a pawl engaging in the said ratchet wheel adapted to thereby arrest the conveyer, means for automatically disengaging said pawl, means for arresting 95 said pawl after its disengagement, two rollers in front of the said conveyer adapted to further advance the sheets, and a feeler between said rollers, adapted to disengage the arresting device for the pawl. 100

In testimony whereof I have hereunto set my hand in the presence of two witnesses.
